UNITED STATES PATENT OFFICE.

ALFRED LOUIS SOHM, OF LOS ANGELES, CALIFORNIA, ASSIGNOR TO SOHM ELECTRIC SIGNAL & RECORDING COMPANY, OF SPOKANE, WASHINGTON, A CORPORATION OF ARIZONA.

TIME-CLOCK MECHANISM.

1,138,989.

Specification of Letters Patent. Patented May 11, 1915.

Application filed September 13, 1910. Serial No. 581,793.

To all whom it may concern:

Be it known that I, ALFRED L. SOHM, a citizen of the United States, and resident of Los Angeles, in the county of Los Angeles and State of California, have invented certain new and useful Improvements in Time-Clock Mechanism, of which the following is a specification.

The object of my invention is to provide a time clock mechanism, electrically operated in order to actuate part of the printing mechanism of a recorder, the necessary number of secondary devices being connected up in multiple, and controlled by a master 15 clock.

I contemplate the provision of a device which is so connected up, operatively, that it will, by the intervention of suitable mechanism, print on a record sheet the work 20 hours, as well as the off hours and also indicate late arrivals, the whole being constructed in a simple manner and absolutely reliable in its operation.

In the drawings, Figure 1 is a diagrammatic view of my system and apparatus. Fig. 2 is a view of the late magnet employed showing the pawl in position when the winding is energized by the current. Fig. 3 illustrates diagrammatically other parts of the 25 recording machine. Fig. 4 is a diagrammatic representation of the master clock in connection with one recording machine and one secondary clock. Fig. 5 illustrates a section of the record taken on the recording machine at the close of the noon hour, and Fig. 6 illustrates the same at the beginning 30 of the morning work period.

In constructing my invention I provide a master clock 3, on the face of which is 40 mounted metallic contact points, two of which, 4, 5, are designed to be engaged by the minute hand 6, and the four points, 7, 8, 9, 10, to engage with the hour hand 11. The point 4 is so located that the minute hand 45 contacts with it one minute before 12 o'clock, and the other point 5, so that the minute hand engages therewith one minute after 12 o'clock. The contact points 7, 8, 9 and 10, 50 are located at the dial figures 12, 1, 5 and 8, respectively.

The second hand has thereon an eccentric wheel 12, and for convenience herein it is located at one side, so as to more clearly illustrate the connecting circuits. The dotted 55 lines in Fig. 1 indicate the position of this

wheel. The recording machine comprises, among other parts to be referred to, a magnet 13, mounted on a suitable base 14, this base having at its projecting end a vertically disposed L-shaped armature 15, hinged 60 thereto at 16, the limb 17 of which is engaged by a spring 18 secured to the base 14, so as to normally throw the armature out of contact with the core of the magnet.

The upper end of the armature 15 has 65 hinged thereto a pawl bar 19, at the opposite end of which is a hinged pawl 20. This pawl coöperates with a ratchet wheel 21, mounted upon an arbor 22. A type-wheel 23 is secured to the arbor 22, and this wheel 70 is provided with two characters 24, oppositely-disposed, as shown. It will be noted that the wheel 21 has 8 teeth so that a clock circuit of this character is designed for four hour shifts, or a work day of eight hours, 75 as will be understood presently.

The eccentric wheel 12 has in engagement therewith one end of a spring finger 25, adapted to ride on the eccentric, and disposed in relation to the fixed finger 26 so 80 that the point 27 of the eccentric will cause the two fingers to contact with each other as shown in Fig. 1.

The circuit is formed by a conductor 28, 85 from the contacts 4, 5, through battery 29, to the fixed finger 26. The spring finger 25 has a conductor 30, which forms a common wire for one side of a series of operating magnets, each designed to have operative means to print characters or record the time. 90 Thus, coil 31 may be located in the recording machine and coil 32 in the secondary clock at the employees' entrance, and in practice any number of clocks may be utilized in the circuit formed by the conductor 30, 95 and by the conductor 33 connected with the other terminals of these coils and running to the other side of the battery 29, all as shown in the drawings, so that all may be controlled by the master clock. 100

One side of the battery is connected up with the coil 13 by a conductor 34, and the other side of the coil 13 has a conductor 35 which runs to the contact points, 7, 8, 9, 10, of the clock. Such a coil is provided for 105 each recording machine as indicated.

A condenser 36 is located between the conductors 30, 34, by wire 37, to prevent arcing at the spring finger 25, and a similar condenser 38 is connected up between conduc- 110

tors 33, 34, by wire 39, to prevent arcing between the clock hands and contact points.

It will now be understood that the electromagnet 13 with the associated parts, and 5 the electromagnet 31, with its time printing wheels 40, which it advances periodically, form part of the recording machine. This machine also comprises the printing electromagnets 41, 41 which are controlled respectively by the switches *a*, *b*, *c*, *d*, and *e*. Any number of such switches may be employed and each workman is assigned to a certain switch. Each magnet 41 operates an armature and associated type bar 42 so that 10 the workman is enabled to print his number on a record sheet by actuating his switch, the current being derived from a battery 43. The common wire 44 of these magnet circuits includes a solenoid winding 45 which 15 operates a core carrying a platen arranged to coöperate with the characters on the time printing wheels 40 and the properly disposed characters on the wheel 23 when the workman operates his switch. The characters 20 on the wheel 23 and those on the wheels 40 are arranged to come in the same "printing line," under this platen and the type 42 are arranged to strike up into this line. The registration on the strip of paper will, for 25 example, be as follows:

Late 26 8:14 AM Jan. 12, 1896.

If the registration is before 8 o'clock for instance, the word "late" of course, will not 30 appear.

The secondary clock 46, which is actuated by the electromagnet 32 may form part of the "entrance plate" containing the switches.

A diagrammatic assembly of the recording 40 apparatus and a secondary clock is shown in Fig. 4 in connection with the master clock, as previously described. But one recording machine and secondary clock is illustrated, but it is obvious that any number of such devices could be connected up in parallel. But 45 one workman's switch *a* is shown in Fig. 4 as well as one electromagnet 41 controlled by said switch *a*. It is apparent that any number of similar switches and magnets 50 could be placed in the circuit. The printing platen 50 is shown controlled by the solenoid 45 in the circuit controlled by switch *a*. The manner in which the type strikes up into a line is also shown in Fig. 4, and Figs. 55 5 and 6 show sections of the printed record taken from the machine. It is now seen that there is a "late" coil in each recording machine which coil is controlled by the master clock.

60 The operation is as follows:—The eccentric mounted on the second hand of the clock, at every complete revolution, connects the impulse fingers, 25, 26, for one second, thereby sending an impulse to coils 31, 32.

65 The secondary clocks, for instance, which

are placed in the circuit between the conductors, 30, 33, will operate in multiple off springs 25, 26, every minute. When the hour hand is at point 10, or eight o'clock and the minute hand is at contact 4 (one 70 minute before 12) the "late" coil 13 becomes energized, thereby pulling up armature 15 and thus moving the ratchet 21 one tooth, which, of course, moves the type wheel 23 a corresponding distance. When the hour 75 hand is on the point 10 and the minute hand at contact 5, showing clock time to be one minute past eight, the "late" coil is again similarly energized and a like action takes place in the type wheel, so that the printing 80 apparatus prints a dash or other character to indicate "late", with the time, day, etc. It will be noted, thus far, that all employees entering before 8:01 a. m. have registered their time without any late character showing upon the record sheet. When the hour 85 hand points to 11:59 a. m. and contacts with point 7, and the minute hand contacts with point 4; the late coil is again energized pulling armature as before, thereby placing the 90 second tooth of the ratchet at the printing point, so that no character will be printed. When the hour hand is at point 7 and the minute hand reaches contact point 5, the late 95 coil is again energized, so that the third tooth is now thrown up, which also results in a blank in the printing apparatus. When the hour hand reaches point 8 and the minute hand touches point 4 another impulse is given to turn the printing wheel another 100 eighth turn and in like manner when the minute hand reaches point 5 another eighth turn is given the printing wheel, thus again exposing one of the characters 24 to the printing mechanism and all employees entering after this time 1:01 p. m. will have the "late" character printed on the time slip until the hour hand reaches the contact point 9 and the minute hand reaches 4 which completes the working cycle.

110 It should be observed that when the hour hand is at point 7 the minute hand will contact with point 5 before the hour hand is released from point 7, thereby again energizing the "late" coil, but must still show a 115 blank character on the printing wheel 23, showing that the character mark shows only from the hours 8:01 to 11:59, and from 1:01 to 4:59, all other contacts showing blank upon the character wheel 23. It will thus be 120 seen that the character wheel has two characters and six blanks for each revolution, corresponding with the eight teeth of the operating wheel.

125 It will be obvious that a number of recording machines, each including a coil 13, may be controlled by a single master-clock.

What I claim as new, is:

1. In a system of the class described, the combination of a master clock, a recording 130

- apparatus, said master clock having a plurality of contact points on its dial for its hour hand, contact points upon its dial for its minute hand, electrical connection between 5 said contact points and an electromagnet in said recording apparatus, and an armature for said electromagnet adapted to control the movement of a character wheel so as to bring said wheel into operative position for 10 registering certain characters during certain periods of time.
2. In a system of the class described, a master clock, a plurality of recording machines, and a plurality of secondary clocks, 15 each of said recording machines having an electromagnet, the armature of which is controlled by said master-clock and adapted to change the position of a character wheel immediately before and after certain hours of 20 the day so as to bring said wheel into or out of position for printing certain characters, and common means for actuating said recording machines and secondary clocks.
3. In a device of the character described, 25 a printing wheel having characters thereon on opposite sides and adapted to print twice during each revolution, a ratchet wheel attached thereto having eight teeth, a magnet coil with an armature operatively connected 30 with said ratchet wheel, a master clock having contact points for the minute hand at the dial figure 12, and contact points for the hour hand at the dial figures 12, 1, 5 and 8, circuits connecting up said magnet coil and 35 contact points whereby the armature will operate to expose the "late" character of the printing wheel between the hours of eight and twelve and one and five.
4. In a device of the class described, the
- combination with time and number printing 40 wheels adapted upon actuation to print a number and the time in a certain printing line, of a printing wheel having tardy characters thereon, a ratchet wheel attached thereto, a magnet coil with an armature operatively connected with said ratchet wheel, 45 a master clock having contact points for the minute hand distributed at certain points, circuits connecting up said magnet coil and contact points so that the armature will operate to maintain the tardy characters of the printing wheel in the printing line between 50 certain hours of the day.
5. In a device of the class described, the combination with time and number printing 55 wheels adapted upon actuation to print a number and time in a certain printing line, of a printing wheel having special characters thereon, a ratchet wheel attached thereto, a magnet coil with an armature operatively connected with said ratchet wheel, 60 a master clock having contact points for the minute hand distributed at certain points, circuits connecting up said magnet coil and contact points so that the armature will operate to change the position of said printing wheel immediately before and after certain 65 hours of the day to maintain the special characteristics in the printing line between certain hours of the day. 70

Signed at Los Angeles, in the county of Los Angeles and State of California, this 6th day of April, A. D. 1910.
